[57] CLAIM

The ornamental design for a skillet, as shown and described.

DESCRIPTION

FIG. 1 is a top front perspective view of a skillet, showing my new design;

FIG. 2 is a left side elevational view thereof;

FIG. 3 is a top plan view thereof;

FIG. 4 is a rear elevational view thereof;

FIG. 5 is a top rear and left side perspective view thereof;

FIG. 6 is a top front and right side perspective view of a second embodiment of that shown in FIG. 1;

FIG. 7 is a left side elevational view thereof;

FIG. 8 is a top plan view thereof;

FIG. 9 is a rear elevational view thereof; and,

FIG. 10 is a top rear and left side perspective view thereof.

The bottom plan views of embodiments 1 and 2 are planar and unornamented.

In both embodiments the bottom plan views are planar and unornamented.

FIG. 3

FIG. 4

FIG. 5

FIG. 6

FIG. 7

FIG.10
